(57) **CLAIM**

The ornamental design for a bowl, as shown and described.

DESCRIPTION

The patent or application file contains at least one photograph executed in color. Copies of this patent or patent application publication with color photograph(s) will be provided by the Patent and Trademark Office upon request and payment of the necessary fee.

FIG. 1 is a top view of a bowl showing my new design;

FIG. 2 is bottom view thereof;

FIG. 3 is a front edge view thereof;

FIG. 4 is a right edge view thereof;

FIG. 5 is a rear edge view thereof; and,

FIG. 6 is a left edge view thereof.

The portions within the broken lines form no part of the claim.

1 Claim, 6 Drawing Sheets
